UNITED STATES PATENT OFFICE.

ANTONI RYBACK AND STANLEY RYBACK, OF DEPEW, NEW YORK.

WINDOW SHADE AND CURTAIN SUPPORT.

Application filed October 29, 1924. Serial No. 746,487.

To all whom it may concern:

Be it known that we, ANTONI RYBACK and STANLEY RYBACK, citizens of Poland and the United States, respectively, residing at Depew, in the county of Erie and State of New York, have invented certain new and useful Improvements in Window Shade and Curtain Supports, of which the following is a specification.

10 This invention relates to window shade and curtain supports, the invention having more particular reference to a support of this type that is adjustable, and is provided with means for supporting both the ordinary 15 spring roller of the vertically movable shade, and the pole for the portières or draperies, the invention having for an object the provision of a novel and improved device of the above sort.

20 For further comprehension of the invention, and of the objects and advantages thereof, reference will be had to the following description and accompanying drawing and to the appended claims in which the 25 various novel features of the invention are more particularly set forth.

Fig. 1 of the drawing is a face view showing our improved curtain supporting device on a window.

30 Fig. 2 is a face view of one of the brackets.

Fig. 3 is a side view thereof.

Fig. 4 is a detail transverse sectional view taken on the line 4—4 of Fig. 2.

35 Fig. 5 is a detail longitudinal sectional view taken on the line 5—5 of Fig. 3.

Fig. 6 is a transverse sectional view taken on the line 6—6 of Fig. 5.

40 Fig. 7 is a horizontal sectional view taken on the line 7—7 of Fig. 2.

Fig. 8 is a fragmentary horizontal sectional view taken on the line 8—8 of Fig. 6.

As here embodied our improved curtain support comprises an angular bracket 10 which is fitted on the usual facing strip F of the window frame, being provided with holes such as 11 to receive fastening screws. The arm of the bracket that projects across the face of the said member F is in the form 45 of a rectangular plate 10' to the face of which is secured a skeleton clamping element 12 that is held in spaced relation with respect to the plate by the ribs 13 that extend vertically along the edge of the latter. 50 Between the clamping element 12 and the plate 10' a vertical strap 14 is positioned

and has an ear 15 projecting laterally therefrom and suitably formed to receive one of the trunnions of the usual spring roller R. The clamping element 12 is secured to the 60 plate 10' by the screws 16 and serves to fix the roller supporting element 15 in place. By loosening these screws the said roller supporting element may be adjusted, across the face of the window frame member F, to 65 bring it nearer to or further away from the corresponding element on the other side of the window.

To support the curtain pole P a rigid post 20 projects upward from the bracket 10 and has a horizontal top piece 21 that extends transversely with respect to the plate 10', that is at right angles to the plane of the window. The curtain pole supporting device comprises a block 23 that extends 70 parallel to the plate and is hollowed out on its upper side as at 24 to receive the end of the pole, this block is mounted on the top piece 21 for adjustment along the latter, being formed near one end with a transverse slot 25 entered upward from the bottom thereof to receive the said top piece. Slidable longitudinally in the lower portion of the block 23 is a bolt 27 that projects at 75 one end through a longitudinal slot 28 in the top piece 21 and has a head 29 thereon formed by a rivet header after said bolt is inserted in the block, said block having on the side remote from said bolt head an opening to allow the insertion of said bolt, and said head 29 after formation is adapted 80 to be clamped on the said top piece. At its other end this bolt is formed with an upwardly projected finger 30 that extends a short distance into the hollow or recess 85 formed in the top of the block. The upper end of this finger is transversely beveled or inclined as shown in Figs. 5 and 8 for a purpose to be presently set forth.

The recess in which the pole P rests is 90 adapted to be covered by means of an angular cover member 33 that comprises a vertical member that extends upward across the end of the block, and a horizontal member that extends along the top of the block, the vertical member being hinged at its 95 lower edge as at 34 to the end of the block at the bottom thereof. To retain this cover element in place, and also to lock the block in adjusted positions on the top piece 21, a stub spindle 36 is rotatably mounted in 100 the vertical member of the said cover ele- 105

110

ment and carries a finger 37 on its inner end that is adapted to engage the finger 30, being beveled on its end complementarily with respect to the latter as shown in Figs. 5 and 8. The outer end of the spindle has fixed thereto an ornamental knob or handle 38 that is designed to have the appearance of the usual ornamental knob on the end of the curtain pole.

- 10 When the curtain pole is to be positioned in the support the knob 38 is rotated to free the finger 37 from engagement with the finger 30, and the cover member 33 is thrown back for insertion of the pole. When the 15 fingers 30, 37 are disengaged from one another the block 23 is free to be adjusted along the top piece 21 to position it at the desired distance from the window frame. After the block has been properly adjusted, 20 and the end of the curtain pole inserted in place, the cover member is swung upward, and the knob 38 rotated to engage the finger 37 with the finger 30 on the bolt, thereby locking the block to the top piece and also 25 securing the cover member in place.

Having thus described our invention, what we claim as new and desire to protect by Letters Patent of the United States is as follows:—

- 30 1. A device of the class described comprising a bracket presenting a longitudinally slotted horizontal top piece, a block slidably mounted on said top piece and having its top side hollowed to receive the end 35 of a curtain pole, a cover member for the curtain pole end hinged to the said block, and means for securing the said block in adjusted positions on the said top piece.

2. A device of the class described com-

prising a bracket presenting a longitudinally slotted horizontal top piece, a block slidably mounted on said top piece and having its top side hollowed to receive the end of a curtain pole, a cover member for the curtain pole end hinged to the said block, and means for securing the said block in adjusted positions on the said top piece, comprising a bolt slidably mounted in the said block and projecting at one end through a longitudinal slot in the said top piece, said end of the bolt having an enlarged head thereon, and means for moving said bolt longitudinally in the said block.

3. A device of the class described comprising a bracket presenting a longitudinally slotted horizontal top piece, a block slidably mounted on said top piece and having its top side hollowed to receive the end of a curtain pole, a cover member for the curtain pole end hinged to the said block, and means for securing the said block in adjusted positions on the said top piece, comprising a bolt slidably mounted in the said block and projecting at one end through a longitudinal slot in the said top piece, said end of the bolt having an enlarged head thereon, and means for moving said bolt longitudinally in the said block.

In testimony whereof we have affixed our signatures.

ANTONI RYBACK.
STANLEY RYBACK.
